MUSICAL TOY BONE OR SIMILAR ARTICLE

Maurice R. Nayer, Detroit, Mich.

Application February 15, 1954, Serial No. 29,031

Term of patent 3½ years

(Cl. D34—15)

Fig. 1

Fig. 2

Fig. 3

Fig. 4

Fig. 5

Fig. 1 is a side elevation view of a musical toy bone or similar article showing my new design;

Fig. 2 is a plan view thereof;

Fig. 3 is a bottom plan view thereof;

Fig. 4 is a section taken on line 4—4 of Fig. 2, and Fig. 5 is a perspective view thereof.

I claim:

The ornamental design for a musical toy bone or similar article, substantially as shown.
